(57) **CLAIM**

The ornamental design for a wall mount light fixture and light fixture sensor, as shown and described.

DESCRIPTION

FIG. 1 is a front perspective view of a wall mount light fixture and light fixture sensor;

FIG. 2 is a front view of FIG. 1;

FIG. 3 is a side view of FIG. 1 with the opposite side being a mirror image thereof;

FIG. 4 is a top side view of FIG. 1; and,

FIG. 5 is a bottom view of FIG. 1.

The broken lines in the drawings illustrate portions of the wall mount light fixture and light fixture sensor which forms no part of the claimed design.
